(57) **CLAIM**

The ornamental design for a spring housing for a door closing device, as shown and described.

DESCRIPTION

FIG. 1 is a front elevation of spring housing for a door closing device showing our new design;
FIG. 2 is a rear elevation thereof;
FIG. 3 is a top plan view thereof;
FIG. 4 is a bottom plan view thereof;
FIG. 5 is a left side elevation thereof;
FIG. 6 is a right side elevation thereof; and,
FIG. 7 is a perspective view thereof, shown in environmental use.

The broken lines environment is for illustrative purpose and forms no part of the claimed design.
